H. E. BARKER

DENTAL DEVICE

Filed Dec. 2, 1927

Inventor
Horace E. Barker
by his Attorney
John J. Noeau

UNITED STATES PATENT OFFICE.

HORACE E. BARKER, OF BROOKLYN, NEW YORK.

DENTAL DEVICE.

Application filed December 2, 1927. Serial No. 237,148.

This invention relates to dental devices, and particularly to an improvement in the teeth-cleaning and gum-massaging device forming the subject of my Letters Patent of the United States No. 1,661,713, dated March 6, 1928, which device, briefly described, comprises a tubular body of soft resilient material divided longitudinally through one side thereof and serrated along its meeting edges 10 to form two opposing series of arcuate rubbing members which are normally held in contracted position by the inherent elasticity of the body, said body having a longitudinally perforated back portion adapted to receive one end of a suitable handle.

The primary object of my present invention is to provide a handle of such construction that by variably turning the same within the perforated back portion the serrated walls 20 of the body are separated or contracted to a greater or less extent against the elasticity of the body so as to facilitate the application of the device to the teeth and gums to be treated, and also to vary or adjust the amount of lateral pressure exerted by the rubbing members 25 upon the opposing surfaces.

Another object is to provide simple and efficient means whereby a bristle brush head can be readily mounted in or removed from 30 the body, as desired.

With these objects in view my invention consists in the combination with the serrated body of the device and its perforated back portion, of a handle of novel construction, and also in the provision of means whereby a brush head can be detachably clamped within the body above its serrated rubbing members, as will be hereinafter described and claimed.

In the drawings—

Fig. 1 is a perspective view of a dental device embodying my invention, the handle being formed and positioned to increase the closed or gripping relation of the rubbing members.

Fig. 2 is an end view of the construction shown in Fig. 1.

Fig. 3 is a similar view of the device as in use, showing the handle as positioned to spread the rubbing members slightly apart 50 and reduce their normal pressure on the gums.

Fig. 4 is a perspective view of a brush head for use in connection with the device.

Fig. 5 is an end view of the device with the brush head mounted therein.

Referring to the drawings, 5 designates a

tubular body of yielding material, such as soft resilient rubber, which is split or divided longitudinally through one side thereof and serrated along its meeting edges to form two opposing series of tapering arcuate rubbing members, 6, of general saw-tooth form which are normally held in closed or gripping relation by the inherent elasticity of the body. These members possess ample firmness to permit and effect the application of dentifrice or other preparation with proper friction to the labial and lingual surfaces of the teeth, but have sufficient flexibility to avoid liability of injury to the soft gum tissues.

The back of the tubular body is formed with a longitudinally perforated projection 9 for the reception of a handle 10 by means of which the device can be manipulated similarly to an ordinary tooth brush.

According to my present invention the perforation 11 in the projection 9, and the insertable end or tang portion, 12, of the handle, are of such relative cross-sectional formation and proportions that by forcibly turning the tang to various diametrical positions in the perforation, the projection is forcibly distorted in a manner to effect either a lateral spreading or a closing of the serrated walls, thus facilitating the application of the device to the teeth and gums when the walls are spread, and also enabling the amount of pressure exerted by the rubbing members upon the opposing surfaces to be varied or adjusted. In the present instance, the perforation 11 is circular in cross-section and the tang 12 is relatively thin and flat with rounded parallel edges 13 and of greater width than the diameter of the perforation. Hence when the tang is forced into the perforation the walls of the projection are expanded and an inner or outward lateral motion, depending upon the relative position of the tang in the perforation, is transmitted through the integral elastic material to the walls of the body; that is to say, when the tang is moved to a horizontal position as seen in Fig. 2, the walls of the projection are horizontally expanded in opposite directions against the inherent elasticity of the material, (as indicated by the arrows *a*) thereby pulling up the top of the body, (as indicated by the arrow *b*) and effecting the movement of the serrated walls toward each other (as indicated by the arrows *c*) in a manner to increase their inward or gripping pressure;

and when the tang is moved to the vertical 105 position as seen in Fig. 3, the walls of the projection are contracted against the inherent elasticity of the material, (as indicated by the arrows *a*) thereby pulling down the top of the body, (as indicated by the arrow *b*) and effecting the movement of the serrated walls away from each other (as indicated by the arrows *c*) in a manner to 110 increase their outward or spreading pressure;

position shown in Fig. 3, the walls of the projection are vertically expanded, thereby reversing the effects just described and causing the partial spreading or opening of the

5 serrated walls in a manner to facilitate the application of the device to the teeth or gums and at the same time reduce the inward pressure of the rubbing members on the teeth or gums under treatment. By varying the angularity of the tang between the horizontal and vertical, the amount of inward pressure of the rubbing members can be nicely adjusted to meet varying requirements.

15 A brush head, as 14, can be detachably mounted with facility within the serrated body, thus permitting the use of a brush in conjunction with the resilient rubbing members, if desired. This brush head, which comprises a rectangular back with bristles, 20 is adapted to be clamped by and between the walls of the body 5 in the space above the rubbing members, said walls being provided with inwardly projecting studs or ledges 15 upon which the back of the brush is supported, as 25 seen in Fig. 5.

I claim—

1. A dental device comprising a tubular body of soft resilient material divided longitudinally through one side thereof and serrated along its meeting edges to form two opposing series of arcuate rubbing members which are normally held in contracted position by the inherent elasticity of the body, said body having a longitudinally perforated 35 back portion, and a handle having a portion adapted to be forcibly inserted in the perforation of the back portion, the relative cross-sectional form and proportions of said handle portion and the perforation being such

that the turning of the handle relatively to 40 the perforation variably expands the walls of the perforation and adjusts the said rubbing members toward or from each other.

2. A dental device comprising a tubular body of soft resilient material divided longitudinally through one side thereof and serrated along its meeting edges to form two opposing series of arcuate rubbing members which are normally held in contracted position by the inherent elasticity of said body, 45 and brush bristles supported within said body in the space above the rubbing members.

3. A dental device comprising a tubular body of soft resilient material divided longitudinally through one side thereof and serrated along its meeting edges to form two opposing series of arcuate rubbing members which are normally held in contracted position by the inherent elasticity of said body, 50 and a brush head clamped by and between 60 the walls of said body in the space above the rubbing members.

4. A dental device comprising a tubular body of soft resilient material divided longitudinally through one side thereof and serrated along its meeting edges to form two opposing series of arcuate rubbing members which are normally held in contracted position by the inherent elasticity of said body, 65 the inner lateral surfaces of said body having inward projections above the rubbing members, and a brush head including a back supported on said projections and clamped by and between the walls of said body.

Signed at New York in the county and 70 State of New York this 29th day of November A. D. 1927.

HORACE E. BARKER.
